UNITED STATES PATENT OFFICE

PETER R. ARONSON, OF BRIDGEPORT, CONNECTICUT, ASSIGNOR TO REMINGTON ARMS COMPANY, INC., A CORPORATION OF DELAWARE

PRIMING MIXTURE

No Drawing.

Application filed June 14, 1928. Serial No. 116,032.

This invention relates to primer compositions or mixtures and particularly to a priming mixture which contains no ingredients that are capable of leaving solid hygroscopic residues in the gun barrel, thereby causing or facilitating corrosion of the barrel.

The purpose of a primer in ammunition being to drive a hot spark into and through the powder charge to effect rapid and complete combustion thereof, commercial priming compositions include three classes of ingredients. The first is an initial explosive, or force producing ingredient; the second a substance which on decomposition yields a large quantity of oxygen. The third is a fuel or substance to be oxidized.

With the advent of modern smokeless and semi-smokeless powders, it became necessary to greatly increase the heat and pressure generated upon the explosion of the priming mixture, thus necessitating a very powerful and dependable oxidizing agent. Potassium chlorate has been quite universally used for this purpose. The combustion of this substance, however leaves a residue of very hygroscopic potassium chloride, which substance solidifies at a comparatively high temperature, and is driven by the high pressures prevailing within the gun barrel into microscopic fissures and indentations in the surface from which it cannot be removed by mechanical swabbing, or by the universally used non-aqueous gun cleaning compositions. Due to its hygroscopic character, the potassium chloride subsequently absorbs moisture and corrodes the gun barrel, even after it has been cleaned and oiled with great care.

For this reason, the need for a priming composition which does not include potassium or other chlorates has long been felt, and many other oxidizing agents have been proposed and tried.

The preparation of a priming composition, however, is a delicate and difficult undertaking, involving many problems besides the yielding of a non-corrosive residue. While the ingredients must be capable of reacting with extreme rapidity when struck a sharp blow they must also remain uncombined in an intimate mixture for an indefinite

time. They must also be incapable of reacting with the metal of the primer cup or shell case. They must likewise remain stable and active for an indefinite time under extreme conditions of temperature and humidity. 55

In the past, various oxidizing nitrates, for example barium nitrate, have been proposed as the oxidizing ingredient of primers. These salts, however, tend to yield their oxygen somewhat slowly, and a very appreciable 60 time interval may under certain circumstances elapse before their maximum heat of reaction is attained. When such a primer is used the propelling charge tends to ignite slowly, rather than to detonate sharply, or 65 if it does detonate, the explosion is retarded. Cartridges in which the propelling charge burns or explodes late are respectively known as "squibs" and "hangfires".

In order to eliminate hangfires in nitrate 70 primers it is sometimes desirable to add an ingredient which will accelerate the reaction. For this purpose an initial explosive, such as mercury fulminate, has been proposed. The present invention, however, contemplates the use as an oxidizer in primers of a true peroxide which is sufficiently non-hygroscopic to remain stable and active under the adverse conditions heretofore mentioned, a true peroxide being understood to be one 75 which reacts with water or acids to form hydrogen peroxide. Prior to the investigation leading to this invention little had been published or known regarding this class of compounds. The number of them at present 80 known to exist is limited, and the related elements are generally found in the third column of the tables of the periodic system. 85

The ingredients of priming compositions must be of low hygroscopicity in order to be 90 free from deterioration under ammunition storage conditions. Actual tests show that the hygroscopicity of the peroxides of the elements in the third column of the periodic table varies progressively according to the 95 position of the elements in the table. The peroxides of the alkali earth metals are quite hygroscopic, but their hygroscopicity decreases with increase in the atomic weights. The known peroxides of the less basic metals

in the right hand group of the third column of the table show a similar variation, and each of these peroxides is less hygroscopic than the peroxide of the alkali earth metal in the same row or series of the table.

The present invention comprises the discovery that the peroxides of the elements other than the alkali earth metals, in the third column of the periodic table, are suitable oxidizing ingredients for priming compositions. While the exact composition of such peroxides may be regarded as somewhat doubtful, their existence has been recognized and they may be prepared by methods which have been described in chemical literature. See for example Chemical Abstracts, vol. 6, page 43. Of these the peroxide of cadmium is particularly desirable, although peroxides of other elements of this group are also suitable. The superiority of cadmium peroxide may be due in part to its lower hygroscopicity. While these substances may be used alone, their use in conjunction with an oxidizing salt, such as an oxidizing nitrate, is preferred. With barium nitrate, for example, the peroxide accelerates combination, making the firing of the cartridge quick and certain. Moreover the composition is not liable to deteriorate under ammunition transportation and storage conditions. The proportions of the ingredients may be varied thru wide limits. A typical highly successful "rim fire" composition has approximately the following composition:

	Per cent
Mercury fulminate	37.4
Lead sulpho-cyanate	9.3
Barium nitrate	23.4
Cadmium peroxide	10.3
Glass	18.7
Gum arabic	0.9

A similar composition adapted for "center fire" ammunition is:

	Per cent
Mercury fulminate	35.4
Lead sulpho-cyanate	8.9
Barium nitrate	36.5
Cadmium peroxide	10.3
Antimony sulphide	8.9

The invention, however, is to be understood as contemplating the use in priming compositions, of true peroxides generally, and particularly true peroxides of the elements, exclusive of the alkali earth metals, in the third column of the periodic table, with any other ingredients, as well as all equivalent compositions which fall within a broad interpretation of the appended claims.

What is claimed is:

1. A priming mixture containing cadmium peroxide.
2. A priming mixture containing a nitrate and cadmium peroxide.

3. A priming mixture containing barium nitrate and cadmium peroxide.

4. A priming mixture containing mercury fulminate, barium nitrate, and cadmium peroxide.

5. A priming mixture containing mercury fulminate, cadmium peroxide, barium nitrate and a fuel.

6. A priming mixture having approximately the following composition:—

	Per cent
Mercury fulminate	37.4
Lead sulphocyanate	9.3
Barium nitrate	23.4
Cadmium peroxide	10.3
Glass	18.7
Gum arabic	0.9

7. A priming composition containing a peroxide of an element in the right hand group of the third column of the periodic table.

8. A priming composition containing a peroxide of an element in the right hand group of the third column of the periodic table, and a fuel.

9. A priming composition containing a combustion initiator, and a peroxide of an element in the right hand group of the third column of the periodic table.

10. A priming composition containing a combustion initiator, a fuel, and a peroxide of an element in the right hand group of the third column of the periodic table.

11. A priming composition containing a combustion initiator with a peroxide of an element in the right hand group of the third column of the periodic table, and a second oxidizing ingredient.

12. A priming composition containing barium nitrate, and a peroxide of an element in the right hand group of the third column of the periodic table.

13. A priming composition containing a combustion initiator, barium nitrate, and a peroxide of an element in the right hand group of the third column of the periodic table, and a fuel.

14. A priming mixture containing a combustion initiator, cadmium peroxide, and a fuel.

15. A priming mixture containing a combustion initiator, cadmium peroxide, and lead sulphocyanate.

16. A priming mixture containing mercury fulminate, cadmium peroxide, and a fuel.

17. A priming mixture containing a combustion initiator, cadmium peroxide, a second oxidizing ingredient, and a fuel.

18. A priming mixture containing a combustion initiator, cadmium peroxide, barium nitrate, and lead sulphocyanate.

19. A priming mixture containing a combustion initiator, cadmium peroxide, a fuel, and an abrasive.

PETER R. ARONSON.
